COMBINATION VACUUM CLEANER AND
BURNER

Henry Leon, Brooklyn, N. Y.

Application March 18, 1946, Serial No. 655,321

4 Claims. (Cl. 183—6)

1

This invention relates to a combination vacuum cleaner and burner and more particularly to a vacuum cleaner and burner that is adapted to be moved about the floor for use in removing dust from rugs, carpets and other floor coverings.

An object of this invention is to provide in combination with a portable vacuum cleaner having an air and dust suction fan, a helical passageway of tubular cross-section in communication with the discharge from the fan, an elongated coil of helically wound wire adapted to be rendered incandescent by resistance to an electric current passing through it mounted in closely confined and in entirely inclosed relation in the passageway, and means for causing incandescence of the wire, whereby air containing dust passing through the passageway and in contact with the incandescent wire will be burned to ashes.

Another object of this invention is to provide in combination with a vacuum cleaner having an air and dust suction fan, an elongated passageway connected with the discharge from the fan, an incandescent electric element co-extensive with the passageway, means for causing incandescence of the element, for burning the dust discharged by the fan and passing in contact with the incandescent element, an ash collecting receptacle in the lower portion of the vacuum cleaner, and a circumscribing chamber having a screen or felted pad at its upper portion for the discharge of clean air from the vacuum cleaner.

Another object of this invention is to provide a modified vacuum cleaner of the class described and comprising a resistance adapted to be rendered incandescent by an electric current passing through it, the resistance being mounted in closely confined relation in a passageway through which the dust laden air is made to pass and to provide a coarse filter below the exit from the passageway and an activated charcoal bed or similar gas absorbing material above the said exit and through which the discharged air will pass and so that the odor resulting from the burning of the dust will be eliminated.

This application is a continuation in part of my abandoned application for patent for Combination Vacuum Cleaner and Burner, Serial No. 508,707, filed November 2, 1943.

With the above and other objects in view, the invention will be hereinafter more particularly described, and the combination and arrangement of parts will be shown in the accompanying drawings and pointed out in the claims which form part of this specification.

2

Reference will now be had to the drawings, wherein like numerals of reference designate corresponding parts throughout the several views, in which:

5 Figure 1 is a central cross-sectional view of the combination vacuum cleaner and burner showing the air suction inlet, the portion below the inlet being taken as on line 1—1 in Figure 2.

10 Figure 2 is a cross-sectional view through the air suction inlet, the section being taken as on line 2—2 in Figure 1, the volute chamber for the fan being partly broken away to show a passageway from the fan discharge to a passageway on the outer surface of the incandescent element.

15 Figure 3 is an elevation of the incandescent heating unit, the incandescent element being removed.

20 Figure 4 is a central cross-sectional view of a modified combination vacuum cleaner and burner comprising a lower coarse filter at the lower level of the vacuum cleaner and a gas adsorbing bed at an upper elevation of the vacuum cleaner.

25 In the illustrated embodiment of the invention, the numeral 10 indicates a tubular blower housing. At its lower end, the housing 10 is pivotally mounted on hinge elements 11 to a hollow bottom member 12. In the member 12 is a receptacle 13 in which is deposited the ash from the burned dust. A door 14 suitably secured to the bottom member 12 enables convenient and clean removal of the ash receptacle from the bottom member.

30 Mounted over the outer periphery of the blower housing 10 is a tubular casing 15 having an annular flange 16. The casing 15 is secured to the housing 10 by screws 17. A disk-shaped fine-mesh air filter 18 preferably made of spun glass is secured to the upper face of the housing 10 by the flange 16.

35 Mounted centrally in the upper portion of the housing 10 is an electric motor 20 and a shaft extension 21 having a centrifugal fan 22 secured thereto. The casing 10 has an aperture 23 permitting passage therethrough of a flexible conduit 24 which is connected to a tubular inlet 25 projecting from the housing. The free end of the conduit is connected to a vacuum cleaner nozzle (not shown).

40 The housing 10 comprises a lower section 10' having a hollow conical extension 31 which terminates at its lower end in spaced relation above the receptacle 13. At its upper elevation, the housing section 10' terminates in a flange 32 of volute form which fits inside a fan enclosing flange 33 of volute form. The housing section 55 10' is secured by screws 34 to the housing 10.

A threaded metallic socket 35 is fixed in the upper portion of the housing section 10'. A terminal 36 is secured by screws 37 to the upper face of the housing section 10' and in spaced relation above the socket 35. An electric cable 38 which is adapted to be connected with a source of electric current enters the vacuum cleaner through apertures in the walls of the casing 15 and of the housing 10 and has two wires, one of which is connected to the free end of the terminal 36 and the other is connected to the socket 35.

The extension 31 has a conically shaped interior which is designed to provide close fitting contacting relation with the exterior surface of a conically shaped heating unit 40. The heating unit 40 has a threaded metallic sleeve member 41 adapted to engage complementary threads within the socket 35. As shown in Figure 1, when the heating unit 40 is in contacting relation with the conically shaped interior 39, a contact 42 on the upper portion of the sleeve member 41 is in electrically contacting relation with the lower face of the terminal 36.

The body of the hollow incandescent unit 40 is made of conically shaped insulating and heat resisting material having a helical groove 40' all around its outer surface. The groove 40' is of substantially semi-circular cross-section and larger than a coiled wire incandescent element 45 which is housed therein. Threaded sockets 43 of insulating material are provided in the housing section 10' for insulating the terminal 36 from the material of the housing section.

Electric current flows through the cable 38 to the incandescent unit 40 and to the electric motor 20 through a cable 48 in parallel with the cable 38.

In operation, current flows from the cable 38 to a terminal 44, to the socket 35, through the coiled wire element 45, and along a straight portion 46 of the wire element 45 in the interior of the unit 40, to the contact 42, and then through the terminal 36 to the cable 38.

As best shown in Figure 2, the volute flange 33 enclosing the fan 22 starts at a point 50 close to the outer periphery of the fan and terminates at a point 51 in considerably spaced relation from the fan. The air discharge from the fan passes into an aperture 52 and into a downwardly directed passageway 53 having a radially directed outlet 54 facing the interior 39 of the conical extension 31. It is to be noted that the outlet 54 is in line with the upper end 55 of the helical groove 40'.

For the purpose of removing heavy foreign objects from the air stream, such as pins 56 made of metal, I provide a trap 57 comprising a passage 58 positioned crosswise of the passageway 53. One of the walls defining the passageway 53 is at height forming a partial bar to the air flow and causes at whirling motion at said wall, whereby the pins, etc., drop down into a reticulated casing 59 of fine mesh through which the air may pass but fine enough to stop outward passage of said pins, etc.

When an accumulation of foreign matter fills the trap 57, screws 60 are removed to permit removal of the casing 59 for cleaning out the trap.

As shown in Figure 1, it will be seen that a chamber or space 61, extending across the entire cross-section of the casing, is positioned between the ash receptacle 13 and the groove 40' shown in Figure 3. Also that the chamber 61 has an upwardly extending continuation 62,

which is co-extensive with the entire height of the casing 15.

It will be seen that, in operation, the discharged material from the groove 40' first passes through the chamber 61 and then through the long chamber extension 62. These large passages are of extensively greater cross-sectional area than the confining passageway 63, to permit reduction in velocity of flow and settling of the ash in the ash receptacle 13 before contacting the filter 18.

Figure 4 shows a modified combination vacuum cleaner and burner 65 which is substantially like the combination vacuum cleaner and burner shown in Figures 1 to 3 inclusive.

The combination vacuum cleaner and burner 65 comprises a coarse filter 66 preferably of annular form. The filter 66 is supported by a funnel shaped member 67 having an upper circular flange 68 which may be frictionally supported on a cylindrical lower portion 69 of a modified incandescent unit 40' which is in all other respects similar to the incandescent unit 40.

The funnel shaped member 67 has a perforated horizontally positioned flange 70 having substantially large perforations 71. The coarse filter 66 is preferably secured to the flange 70 by rivets 72.

The combination vacuum cleaner and burner 65 also comprises a chemical gas absorbing bed 75 which may be in the form of activated charcoal 76. The chemical bed 75 is carried in a dished member 77 having a perforated base 78 and perforations 79. The dished member 77 has a horizontal flange 80 resting on the upper portion of the modified housing 10'.

At the upper end of the housing 10' is a fine filter 18 which rests on the flange 80. An annular clamp ring 81 secures the filter 18 and the chemical bed 75 to the housing 10' by the screw 17.

It is to be noted that the motor 20 shown in Figures 1 to 3 inclusive is concealed by an inner cylindrical upper extension 82 of the modified housing 10'.

It is to be noted that, instead of the heating element being an insertable member in a conical housing an equivalent structure may be provided by forming a helical groove in a heating unit inside the housing and a solid cone inserted in the housing for closing or finishing the grooved passageway.

In accordance with the patent statutes, I have described and illustrated the preferred embodiments of my invention, but it will be understood that various changes and modifications can be made therein without departing from the spirit of the invention as defined by the appended claims.

I claim:

1. In a dust burning vacuum cleaner comprising a casing, a suction fan and an ash receptacle, said fan being enclosed in its entirety within said casing, an electric unit having a helical groove on its outer surface, said casing having a housing for receiving said electric unit, said housing covering said grooved outer surface and forming an elongated helical tubular passageway, said passageway communicating at one end with the discharge from said fan and terminating at said ash receptacle at the opposite end, said electric unit comprising a coiled wire incandescent element housed in said tubular passageway in closely confined and in entirely closed relation, said electric element being co-

extensive with said passageway, a tubular conduit for air suction connected to said casing and communicating with the inlet to said fan, means for rotating said fan, means for causing incandescence of said electric element, whereby air containing dust sucked into said fan is constrained to move in contacting relation with said confined incandescent element all along its length and said dust is burned to ashes, said casing forming a chamber positioned between said passageway outlet and said ash receptacle having an extension co-extensive with the entire height of said casing, said chamber and extension being of extensively greater cross-sectional area than said passageway to permit a reduction in velocity of flow and settling of said ash in said ash receptacle, and a screened outlet positioned in spaced-apart relation from said ash receptacle for the escape of dustless air from said dust burning vacuum cleaner.

2. In a dust burning vacuum cleaner comprising a casing, a suction fan and an ash receptacle, said fan being enclosed in its entirety within said casing, an electric unit having a helical groove on its outer surface, said casing having a housing for receiving said electric unit, said housing covering said grooved outer surface and forming an elongated helical tubular passageway, said passageway communicating at one end with the discharge from said fan and terminating at said ash receptacle at the opposite end, said electric unit comprising a coiled wire incandescent element housed in said tubular passageway in closely confined and in entirely inclosed relation, said electric element being co-extensive with said passageway, a tubular conduit for air suction connected to said casing and communicating with the inlet of said fan, means for rotating said fan, means for causing incandescence of said electric element, whereby air containing dust sucked into said fan is constrained to move in contacting relation with said confined incandescent element all along its length and said dust is burned to ashes, said casing forming a chamber positioned between said passageway outlet and said ash receptacle and having an extension co-extensive with the entire height of said casing, said chamber and extension being of extensively greater cross-sectional area than said passageway to permit reduction in the velocity of flow and settling of said ash in said ash receptacle, and a screened outlet positioned in spaced-apart relation from said ash receptacle for the escape of dustless air from said dust burning vacuum cleaner, and means positioned in the passageway from said fan to said electric unit for trapping and collecting metallic substances passing through said passageway and before contacting said electric unit.

3. In a dust burning vacuum cleaner comprising a casing, a suction fan and an ash receptacle, an electric unit having a helical groove, said casing having a housing for receiving said electric

unit, said housing covering said grooved outer surface and forming an elongated helical tubular passageway, said passageway communicating at one end with the discharge from said fan and terminating at said ash receptacle at the opposite end, said electric unit comprising an incandescent element housed in said tubular passageway in closely confined and in entirely inclosed relation, a conduit for air suction connected to said casing and communicating with the inlet of said fan, means for rotating said fan, means for causing incandescence of said electric element, whereby air containing dust sucked into said fan is constrained to move in contacting relation with said confined incandescent element along its length and said dust is burned to ashes, said casing forming a chamber positioned between said passageway outlet and said ash receptacle and having an extension co-extensive with the height of said casing, said chamber and extension being of extensively greater cross-sectional area than said passageway to permit reduction in the velocity of flow and settling of said ash in said ash receptacle, a coarse screen positioned directly above said ash receptacle, and a gas adsorbing bed positioned above said screen.

4. In a dust burning vacuum cleaner comprising a casing, a suction fan and an ash receptacle, an electric unit, said casing having a housing for said electric unit, a tubular passageway communicating at one end with the discharge from said fan and terminating at said ash receptacle at the opposite end, said electric unit comprising an incandescent element housed in said tubular passageway in inclosed relation, a conduit for air suction connected to said casing and communicating with the inlet of said fan, means for rotating said fan, means for causing incandescence of said electric element, whereby air containing dust sucked into said fan is constrained to move in contacting relation with said inclosed incandescent element along its length and said dust is burned to ashes, said casing having a chamber positioned between said passageway outlet and said ash receptacle, said chamber being of greater cross-sectional area than said passageway to permit reduction in the velocity of flow and settling of said ash in said ash receptacle and a gas adsorbing bed in said casing.

HENRY LEON.
